United States Patent Office

Des. 206,863
Patented Feb. 7, 1967

206,863

DISPENSING ISLAND

Eliot F. Noyes, New Canaan, Ernest M. Bevilacqua, Wilton, and Robert E. Graf, New Canaan, Conn., assignors to Mobil Oil Corporation, a corporation of New York

Filed Mar. 21, 1966, Ser. No. 1,572

Term of patent 14 years

(Cl. D13—1)

FIG. 1

We claim:

The ornamental design for a dispensing island, as shown and described.
